UNITED STATES PATENT OFFICE

133,172

DESIGN FOR A COMBINED INNERSOLE AND OUTERSOLE AND HEEL FOR A SHOE OR SIMILAR ARTICLE

Irving Block, New York, N. Y.

Application May 8, 1942, Serial No. 106,829

Term of patent 3½ years

To all whom it may concern:

Be it known that I, Irving Block, a citizen of the United States of America, residing in New York city, county of New York, and State of New York, have invented a new, original, and ornamental Design for a Combined Innersole and Outersole and Heel for a Shoe or Similar Article, of which the following is a specification, reference being had to the accompanying drawing, forming part thereof,

Fig. 1 is a perspective view of a combined innersole and outersole and heel for a shoe or similar article, showing my new design; and

Fig. 2 is a side perspective view with the two parts separated from each other.

I claim:

The ornamental design for a combined innersole and outersole and heel for a shoe or similar article, substantially as shown.

IRVING BLOCK.
